METHOD OF PRODUCING HOSIERY

James Oliver, Ventnor, N. J., and Thomas A. Oliver, Jenkintown, Pa.

Application August 21, 1931, Serial No. 558,614

3 Claims. (Cl. 66—183)

This invention relates to hosiery and more particularly to what is generally known in the art as "net" hosiery, that is, stockings having leg and instep portions composed of open mesh or lace fabric.

Prior to this invention net hosiery has been made upon flat knitting machines equipped with jacquard or other lace attachments adapted to effect the transfer of stitches from needle to needle, in order to form the open mesh fabric in the leg and instep portions of the stocking.

It is generally recognized in the art that the production of net hosiery on knitting machines, due to the necessity of transferring large numbers of stitches, is quite slow; and that the percentage of seconds, due to such transferring of stitches, is relatively high.

To overcome these disadvantages attempts have been made to cut the leg and instep portions of a net stocking from a piece of lace and to apply a knitted foot and welt thereto, to complete the stocking, but due to the flimsy nature of ordinary lace fabric such attempts have not been satisfactory, as it has been found to be practically impossible to obtain leg and instep portions of uniform size and shape.

Another difficulty encountered in connection with such endeavor resides in the inability to secure the knitted foot and welt to the cut edges of the lace piece in a satisfactory manner due to the irregularity and unevenness of the cut edges of the lace.

The principal object of this invention is to construct the leg and instep portions of a net stocking of lace or open mesh fabric in the form of a shaped blank having regular even edges, in order that a knitted foot and a knitted welt may be readily secured thereto and in order that the opposite edges of the leg portion of the blank may be readily secured together by the smallest possible seams at the junctures.

The formation of the shaped blanks with regular even edges has been found to be most efficiently produced on a conventional type of lace loom, preferably a lace loom such as that employed in the making of lace curtains, the pattern mechanism of the lace-making machine being set up in such a manner that a large number of uniform stocking blanks will be produced at one time in a single sheet, the sheet having lines of demarcation defining the individual blanks and functioning as a means whereby the blanks may be readily separated from the adjacent portions of the sheet, each blank being provided, adjacent the regular even edges thereof,

with a strip of solid fabric, to provide for the seaming or looping of the edges of the stocking parts.

Each blank may be composed of any suitable form of mesh fabric capable of being produced on a lace curtain machine, such as a fabric having one form of mesh throughout or a fabric having a mesh background provided at desired places with any suitable form of design.

The construction of the stocking and the process of making the stocking will be more fully disclosed hereinafter, reference being had to the accompanying drawings, of which:

Fig. 1 diagrammatically illustrates a portion of a sheet of fabric as produced on a lace loom of conventional type, wherein the sheet is composed of a plurality of uniform stocking blanks defined by lines of demarcation;

Fig. 2 diagrammatically illustrates one of the blanks after its removal from a sheet such as that shown in Fig. 1;

Fig. 3 diagrammatically illustrates a side view of a completed net stocking formed from a blank such as that shown in Fig. 2 and having a knitted welt and foot attached thereto;

Fig. 4 is a fragmentary view diagrammatically illustrating one form of mesh fabric having the lines of demarcation formed therein, with each blank having an even regular edge and solid seaming fabric adjacent thereto;

Fig. 5 is a diagrammatic view showing an alternate arrangement of blanks in a sheet; and

Fig. 6 is a fragmentary view of a stocking similar to that shown in Fig. 3 and illustrating a seamless foot applied thereto.

Referring more particularly to Fig. 3, a stocking made in accordance with the principles of this invention comprises an upper leg portion 1, a fashioned calf portion 2, an ankle portion 3 and an instep portion 4; all composed of open mesh fabric and produced as a unit on a conventional type of lace-making machine. The stocking also includes a knitted foot structure and a knitted welt formed in any of a number of different ways as will be fully disclosed hereinafter.

Referring now to Fig. 2, it will be noted that the blank A includes the upper leg portion 1 having substantially parallel marginal edges 1a and 1b respectively, the fashioned calf portion 2 having converging marginal edges 2a and 2b respectively, which extend at an angle from the marginal edges 1a and 1b of the leg portion 1 to the substantially parallel marginal edges 3a and 3b of the ankle portion 3 of the blank.

Depending from the ankle portion 3 of the blank A is the instep portion 4, which is of lesser width than the ankle portion 3 and is defined by substantially parallel side edges 4a and 4b respectively, which are offset with respect to the marginal edges 3a and 3b of the ankle portion 3, said offsets being defined by transversely extending marginal edges 5a and 5b respectively.

As shown in Fig. 3, the edges 5a and 5b of the blank A constitute the lines in the stocking where the upper edge of the heel portion 5 of the knitted foot structure joins with the ankle portion 3 of the open mesh fabric of the stocking.

The instep portion 4 terminates at a transversely extending line 6a, as shown in Fig. 2, and which, as shown in Fig. 3, constitutes the line in the stocking where the open mesh fabric of the instep 4 joins with the knitted fabric of the upper portion 6 of the toe pocket of the stocking, the edges 20 of the knitted sole portion 7 of the stocking and the inner edges 5c of the knitted heel portion 5 being joined with the open mesh fabric of the instep portion 4 along the marginal lines 4a and 4b at the opposite sides of the stocking respectively.

The upper leg portion 1 of the blank A terminates at a substantially transversely extending line 10a which, as illustrated in Fig. 3, constitutes the line in the stocking where the knitted welt 30 or garter reinforcement 9 is attached to the open mesh fabric of the leg portion 1 of the stocking.

The stocking blank shown in Fig. 2 is substantially straight along its marginal edges from the fashioned calf 2 to the top edge 10a of the blank, 35 but it will be here noted that if it is desired to widen the stocking blank adjacent the upper end thereof, below the welt 9, such widening may be effected in the same manner as the shaping of the calf portion 2. However, for the purpose of economy in producing stockings in accordance with the principles of this invention the top narrowing has been eliminated, the open mesh of which 40 the fabric is composed having sufficient lateral resiliency to enable the stocking to fit the leg of 45 the wearer above the knee without the necessity of providing any additional widening of the blank.

It will be noted that the blank as shown in Fig. 2 is provided along the line and extending 50 above the line 10a of the blank with plain solid fabric 10 and depending from the lines 5a, 5b and 6a similar pieces of fabric 11, 11 and 12 respectively are provided for the purpose of facilitating handling the blank and more readily applying the foot and welt to the blank in completing the stocking. The fabric portions 10, 11 and 12 may be removed before or after the welt and foot portions of the stocking are applied as desired. In some instances the fabric 10 at the 55 upper edge of the blank may be permitted to remain on the blank to be included in the welt 9 if desired.

As shown in Fig. 1, a plurality of blanks A, A are formed in a sheet with the edges 1a and 1b of adjacently disposed blanks positioned parallel to each other and joined together in a manner to form a line of demarcation therebetween, as indicated at 15. The line of demarcation is forked 65 at the line of juncture of the leg 1 and calf 2, following and defining the marginal edges 2a and 2b of the fashioned calf portions 2, 2 of adjacent blanks as indicated at 15a, 15a, the adjacent blanks being spaced at the fashioned calf portions 2, 2 by an intermediate portion 16a of the 70 sheet, while the ankle portions 3, 3 of the blanks

are spaced by portions 16b of the sheet, between which and the marginal edges 3a and 3b of the ankle portions 3 extend the lines of demarcation as indicated at 15b, 15b. The lines 15b terminate at transversely extending lines of demarcation 15c, 15c which are disposed between the lower edges of the handling fabric 11, 11 and upper edges of a third intermediate portion 16c of the sheet. The instep portions 4, 4 of the blanks A, A respectively are defined by lines of demarcation 15d, 15d which extend between the marginal edges 4a and 4b of the instep portions 4, 4 and the portions 16c of the sheet, the lines of demarcation 15d extending from the lower end of the handling fabric 12 of each blank A to the lines 5a and 5b of the blanks.

Fig. 4 illustrates one method of producing the lines of demarcation in the sheet, and to those familiar with the art of lace making, and particularly the manufacture of lace curtains as produced on lace curtain looms, the construction of the lacework and the manner of producing the sheet of mesh fabric having the lines of demarcation therein, with regular even edges on the individual blanks and the solid seam'g fabric in the blanks adjacent the said edges of the blanks, will be readily understood upon referring to Fig. 4.

Lace curtain fabric, briefly, comprises longitudinally extending warp threads, such as those indicated at 25, which normally hang in parallel relation to each other in the loom. During the weaving of the lace fabric these warp threads are drawn toward each other and joined together at various places and in a predetermined manner, to form the open mesh fabric, by transversely extending threads 26, which are carried by suitable shuttles that pass between the warp threads and are then shogged laterally, passing again between the warp threads in a reverse direction 115 in order to wrap the shuttle threads around the warp threads.

The net shown in Fig. 4 is one of the simplest forms of lace fabric to produce on the conventional type of loom and is intended for the purpose of illustration only, as it will be noted that any desired form of mesh, with or without other designs formed therein, may be provided without departing from the essential features of the invention.

Cutting of this type of lace fabric under ordinary conditions would produce irregular uneven edges along the line of the cut, due to the cut passing through the open meshes of the fabric, and in order to provide even regular edges on each blank the warp threads 25 at and adjacent the lines on which the sheet is to be cut are maintained in substantially straight parallel relation to each other, by wrapping of the shuttle threads 26 around the parallel warp threads, thereby producing strips of solid fabric in the sheet at such places where the sheet is to be cut.

In order to provide the lines of demarcation in the sheet, to facilitate the cutting of the sheet 140 into individual blanks of uniform size and shape, a relatively open space is provided in or adjacent each of the strips of solid fabric, these open spaces being crossed by threads 27, which connect the parallel edges of the solid fabric parts 30, 30 145 of the adjacently disposed portions of the sheets and thereby produce the readily discernible lines of demarcation in the sheet, such as indicated at 15 in Fig. 4, thus when the fabric is cut along the lines of demarcation, by severing the connect- 150

ing threads 27, regular even edges will be produced on each blank.

The solid fabric parts 30 adjacent the edge of each blank provides for the seaming of the edges 5 of the blank together or to the edges of the other components of the stocking and provide for the making of small strong and straight seams.

After the blanks A, A have been parted the welt structure and the foot structure are applied 10 thereto in any suitable manner, for example the welt structure 9 may be made as a flat piece of knitted fabric on any type of knitting machine, after which the strip of knitted fabric may be folded upon itself and the fabric 10 at the upper 15 end of the blank A may be inserted between the folds of the knitted fabric which are then stitched, looped or otherwise seamed at or adjacent the line 10a to join the welt structure with the leg portion 1 of the stocking. Obviously, the welt 9 20 may be made on a circular knitting machine in the form of a tube and applied to the top edge of the blank A in a similar manner.

It is also within the scope of the invention to apply the upper end of the blank A, at or adjacent the line 10a, to the needles of a knitting machine and to knit a welt structure directly to the blank as a single ply welt with a non-raveling edge or as a double ply welt folded upon itself around the top edge of the blank A, to include 30 a portion of the fabric adjacent the top edge of the blank A, and then topped onto the needles again, after which a few additional courses of stitches may be knitted to lock the welt and fabric of the blank A together. The knitted fabric may 35 then be knit off the needles and an overedge stitching applied to include the last courses formed to prevent raveling thereof.

The foot structure likewise may be applied in a number of different ways and may be of various 40 forms, for example, a foot known as a "French foot" may be employed. In forming this type of foot the heel pieces 5, 5 may be formed on any suitable type of a knitting machine, after which the portions along the inner edges of a pair of 45 heel pieces 5, 5 between the points x and y may be topped onto the needles of a flat knitting machine in spaced relation to each other, with the points x, x of the pair of heel pieces 5, 5 separated a distance equal to the width of the instep 50 portion 4 of the blank A. The two halves of the foot sole 7 are then interknit with the heel pieces 5, 5 respectively along the lines z, the knitting of the foot sole parts continuing until fabric is produced to an extent equal to the length of the 55 marginal edges 4a—4b of the instep 4, whereupon the knitting of the upper portion 6 of the toe is begun on the needles intermediate the separated groups that have been knitting the two separate parts of the foot sole 7. The knitting of the top 60 portion 6 of the toe and the bottom portion 7a of the toe progresses simultaneously, the toe including the portions 6 and 7a being narrowed and shaped in the usual way.

A foot known as an "English foot" may be 65 employed as shown in Fig. 3. In forming this type of foot the heel pieces 5, 5 may be formed on any kind of a knitting machine and the portions along the inner edges between the points x and y may be topped onto the needles of a flat knitting machine with the points y, y of a pair of heel pieces 5, 5 in abutting relation to each other. The knitting of the foot sole 7 is then carried on in the usual manner, being interknit solidly with the heel pieces 5, 5 along the lines z, the toe portion 7a being narrowed and shaped

in the usual way. The upper toe portion 6 is also knit on a flat machine and fashioned in the usual manner, after which this upper toe piece 6 is joined to the lower toe portion 7a of the sole structure 7 along the line w as by any of the usual seaming or looping methods.

The assembled foot structure, in either case, including the heel pieces 5, 5, the foot sole 7 and lower toe portion 7a, and the upper toe portion 6 are then applied to the blank A, by being 80 looped, sewed or otherwise seamed to the edges 4a, 4b, 5a, 5b and 6a of the blank A in the manner indicated in Fig. 3.

In the case of the "English foot", the lower 85 ends of the heel pieces or tabs 5, 5 between the points y and y¹ are then looped together in the usual manner and the two edges at the opposite sides of the blank A are then seamed together in the usual manner from the point y¹ to the top of the stocking to complete the stocking.

In the case of the "French foot" the seam begins as usual at the point of the toe and extends along the sole of the foot and up the back of the leg, thereby joining the edges of the two parts of the foot sole and the opposite edges of the leg portion of the blank to complete the stocking.

If desired, the foot structure may be made in one piece as a seamless unit, on a circular knitting machine, including a full seamless heel 55, 105 a full seamless foot sole 77, with a full seamless heel pocket 88 intermediate the sole and the heel, and a full seamless toe pocket 66, the edges 55a, 55b, 66a and 77a of which are joined to the edges 5a, 5b, 4a, 4b and 6a of the blank A in 110 the same manner as the corresponding edges of the foot structure shown in Fig. 3.

Fig. 5 of the drawings illustrates a sheet of mesh fabric composed of stocking blanks A and A¹ arranged in rows with the instep portions of 115 the A¹ row alternating with and disposed intermediate the blanks A of the other row, whereby the quantity of material of the sheet which must be wasted when the blanks are separated along the lines of demarcation 15, 15a, 15b, 15c, 15d will 120 be reduced to a minimum as indicated at 16d and 16e.

In order to facilitate the handling of the blanks and to prevent the edges of the blanks from curling, the blanks either before or after being separated from the sheet, preferably before, are sized with a suitable substance such as starch, and preferably pressed or ironed, as by a mangle. In this way the seaming fabric 30 may be reduced to a minimum in width and still permit 125 the operator to readily join and seam the stocking along the lines of juncture, whereby extremely small but secure straight seams may be made.

We claim:

1. The method of producing net hosiery which consists in making and shaping the leg and instep portions of a stocking on a lace-making machine in the form of a blank, sizing the blank, pressing the sized blank, applying a knitted foot 130 and welt to the blank and subsequently uniting the unjoined portion of the stocking structure to complete the stocking.

2. The method of producing net hosiery which consists in making and shaping the leg and instep portions of the stocking on a lace-making machine in the form of a blank, applying the blank to the needles of a knitting machine, knitting a predetermined number of courses of the 135 welt fabric, topping a primary course of the welt 140

fabric stitches on the needles to form a double
ply welt, knitting a number of courses after said
topping, and locking the last course against raveling.

- 5 3. The method of producing net hosiery which
consists in making and shaping the leg and in-
step portions of the stocking on a lace-making
machine in the form of a blank, applying the
blank to the needles of a knitting machine, knit-
ting a predetermined number of courses of the

welt fabric, doubling the knitted fabric over the
top edge of the blank to form a two ply welt
with the blank fabric between the plies, topping
a primary course of the welt fabric stitches on
the needles to form the double ply welt, knit-
ting a number of courses after said topping, and
locking the last course against raveling.
